Primary Examiner — Messina L Smith(74) *Attorney, Agent, or Firm* — QUICKPATENTS, LLC;
KEVIN PRINCE(57) **CLAIM**

The ornamental design for a food steamer pan insert, as shown and described.

DESCRIPTION

FIG. 1 is a front elevational view of a food steamer pan insert, showing our new design in an environment of use, with the rear, left-side, and right-side elevational views being identical thereof;

FIG. 2 is a top perspective view of the food steamer pan insert;

FIG. 3 is a top plan view thereof;

FIG. 4 is a bottom view thereof; and

FIG. 5 is a cross-sectional view of the food steamer pan insert taken in the direction of line 5-5 in FIG. 3.

The broken lines showing a sauce pan and lid in FIG. 1 depict environmental matter and form no part of the claimed design. The apertures shown in FIG. 5 in cross-section are representative of all of the apertures shown in the drawings.
